CLAIM

The ornamental design for a protection cover for padlock, as shown and described.

DESCRIPTION

FIG. 1 is a perspective view of a protection cover for padlock showing my new design;

FIG. 2 is front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof, shown in the environmental use applied to a padlock; and,

FIG. 9 is a perspective view thereof, shown in environmental use applied to a padlock and in open position.

The broken lines showing environment is for illustrative purpose only and form no part of the claimed design.
